INVENTOR

Himan Garfinkel

BY

Minn Co.
ATTORNEYS

UNITED STATES PATENT OFFICE.

HIMAN GARFINKEL, OF CORONA, NEW YORK.

UMBRELLA.

Application filed August 28, 1922. Serial No. 584,828.

To all whom it may concern:

Be it known that I, HIMAN GARFINKEL, a citizen of the United States, and a resident of Corona, borough of Queens, in the county of Queens and State of New York, have invented a new and Improved Umbrella, of which the following is a full, clear, and exact description.

This invention relates to umbrellas and has particular reference to an improvement in the means of connection between the elements which constitute the frame.

At the present time it is the common practice to pivot the spreaders and ribs to the runner and rib bearing member by means of very thin wires, which, in a limited space of time rust and wear under the constant strain of opening and closing the umbrella, thus necessitating replacement of the wires and often the discarding of the entire umbrella.

It is therefore an object of the present invention to provide at the pivotal points of the ribs and spreaders and at the points of connection between said elements, means for reducing friction and wear in order to increase the life and usefulness of the frame to a maximum.

As a further object the invention contemplates means for strengthening the frame structure at the points of connection between the elements which go to make up the frame.

The invention further contemplates an umbrella frame structure which embodies a staff having detachable portions at the opposite ends whereby the length of the umbrella may be reduced to allow for the packing of the same in a suitcase or other similar carrying case.

The invention furthermore contemplates an improved umbrella frame which does not materially increase the cost of production, which is strong and durable in its construction and which is easily operated without binding or sticking.

With the above recited and other objects in view, the invention resides in the novel construction set forth in the following specification, particularly pointed out in the appended claims and illustrated in the accompanying drawing; it being understood that the right is reserved to embodiments other than those actually illustrated herein to the full extent indicated by the general meaning of the terms in which the claims are expressed.

In the drawing—

Figure 1 is a fragmentary sectional view through an umbrella constructed in accordance with the invention.

Fig. 2 is an enlarged sectional plan view taken approximately on the line 2—2 of Fig. 1.

Fig. 3 is a transverse sectional view taken approximately on the line 3—3 of Fig. 2.

Fig. 4 is a sectional view taken approximately on the line 4—4 of Fig. 1.

Fig. 5 is a fragmentary sectional view taken on the line 5—5 of Fig. 4.

Fig. 6 is a sectional plan view similar to Fig. 2, illustrating a slightly modified form of the invention.

Fig. 7 is a fragmentary sectional view similar to Fig. 5, illustrating a further modification.

Fig. 8 is a fragmentary sectional view of another modification.

Fig. 9 is a similar view of a further modification.

Fig. 10 is a similar view of a still further modification.

Referring to the drawing by characters of reference, 10 designates the staff or stick of an umbrella which is provided with an externally threaded extremity 11 and a reduced threaded opposite end 12 which is designed to be screwed into the threaded socket 13 of a handle section 14. A stationary bearing sleeve 15 which is internally threaded as at 16 receives the threaded extremity 11 of the staff. The stationary bearing sleeve is preferably of annular formation and is provided with a circular groove or passageway 17 in its upper face and radially disposed slots 18 in its outer edge which are intersected by the groove 17. The ribs which are indicated at 19 and which are preferably of U-shaped formation in cross section are provided at their upper extremities with heads 20, the shanks 21 of which are inserted in and riveted as at 22 to the ribs. The heads are provided with transverse sockets 23 in one face to constitute a ball race to receive the ball bearings 24 and a closure plate 25 is insertable in the outer end of the socket to lie flush with the side face of the head. An opening 26 disposed axially with respect to and communicating with the socket 23 is also disposed in alignment with a central opening 27 in the cover plate. The rib heads 20 are snugly fitted in the slots 18 with the aligned openings 26 and 27 registering with

the passageway or groove 17. Bearing pins 28 are inserted through the openings 26 and 27 prior to the assembly of the rib heads with the bearing member and the opposite 5 ends of said bearing pin are tapered as at 29. After the ribs are assembled with the stationary bearing sleeve 15, a cover disk 30 of the same diameter as the bearing sleeve 15 is arranged thereover. The cover disk is 10 provided with a centrally threaded opening 31. The threaded extremity 11 extends approximately half way through the central threaded opening 16 and a staff extremity or section 32 is threaded through the threaded opening 31 of the cover disk and into threaded opening 16 of the bearing member 15. A runner consisting of a thimble 33 provided with a threaded end 34 is screwed into the movable bearing sleeve 35 which is of 15 substantially identical construction to the stationary bearing sleeve. The spreaders designated by the character 36 are provided respectively at their opposite ends with heads 37 and 38, the former being mounted between 20 the spaced ears 39 of a bearing member 40 which is riveted as at 41 to the ribs; the latter head 38 is received in the slots of the movable bearing sleeve 35 of the spreader and each of said heads is provided with a 25 ball race and ball bearings identical with the construction described for the heads 20 of the rib members.

From the foregoing it will be appreciated that an umbrella frame structure has been 30 provided in which the connections and pivotal points of the ribs and spreader members are guarded against friction and wear to increase their length of usefulness and at the same time render the operation of 35 opening and closing the umbrella free from binding or sticking. It is also evident that the handle 14 and the terminal 32 of the staff may be detached for reducing the length 40 of the umbrella whereby the same may be packed in a suitcase or other carrying case.

In the modified adaptation of the invention illustrated in Fig. 6, a single continuous annular bearing pin 42 is employed in lieu of the separate bearing pins 28, the same 45 being of a proper diameter to properly lie within the groove or passageway 17 of the stationary and movable bearing sleeves 15 and 35.

In the modified form of the invention illustrated in Fig. 7 the spreader or rib heads 20, 37 or 38 may be used without the ball bearing, if desired.

In the modifications illustrated in Figs. 8 and 9, the thimble 33 and the staff extremity 60 32 may have a friction fit in the movable and stationary bearing sleeves 35 and 15.

In the modified form illustrated in Fig. 10 the bearing sleeves in lieu of having the

cover plate may be constructed in two sections 43 and 44, the confronting faces of 65 which are provided with complementary annular grooves of passageways 45 for the bearing pin or pins 28 and 42. In this instance the sleeve sections are provided with complementary central threaded openings 46. 70

I claim:

1. An anti-friction connection for the pivotally joined elements of an umbrella frame, comprising a member having spaced bearing ears carried by one of the joined elements, a pivot extending through said ears, a member carried by a second frame element and disposed between said bearing ears, said latter member being provided with a socketed portion having a concentric aperture and a concentrically apertured closure plate for the socketed portion through which apertures the pivot extends the said socketed portion defining a ball race, and anti-friction balls within said race disposed around the pivot pin. 80

2. An umbrella frame including ribs, spreaders, a staff and stationary and movable bearing sleeves associated with the staff, said stationary bearing sleeve having circumferentially spaced bearing ears, a pivot extending across each pair of bearing ears, a member carried by each rib and disposed respectively between the pairs of bearing ears, said member being provided with a recess in one side thereof having a concentric bearing aperture in its side wall and said recess constituting a ball race, a cover plate fitted within the open side of the recess provided with a concentric aperture in 100 alignment with the first aperture and said apertures receiving therethrough the pivot, and a plurality of anti-friction balls within the recess and interposed between the periphery thereof and the periphery of the 105 pivot pin.

3. In an umbrella frame including ribs, spreaders, a staff and stationary and movable bearing sleeves associated with the staff, of anti-friction joints for pivotally connecting the elements of said frame, comprising a member having spaced bearing ears carried by one element of each joint, a member carried by the second element of each joint including a headed portion having a recess in one of its sides, a closure plate disposed within the open side of the recess, said closure plate and the opposite wall of the recess having aligned apertures, a pivot pin extending therethrough and received at its 110 opposite ends by the spaced bearing ears, and a plurality of anti-friction balls within said recess and disposed between the periphery of the pivot pin and the walls of the recess. 115

HIMAN GARFINKEL.
